AIR JET FOR SANDBLASTING APPARATUS

Edward J. Flavin, Grand Coulee, Wash.

Application February 8, 1939, Serial No. 255,331

1. Claim. (Cl. 51—8)

This invention appertains to new and useful improvements in sandblasting apparatus and more particularly to an air jet for use in conjunction therewith.

5 In large dam construction projects many thousand square feet of concrete must be sandblasted as course upon course of concrete work is built up, so that there will be perfect bondage between the courses. In starting a dam project and during construction work thereon, a trestle is located over the operations and upon this rolling stock is moved to a position over any point to which materials must be delivered.

An important object is to provide a sandblasting apparatus which will involve a hopper adapted to be suspended from the trestle of a dam construction, and which has a sand supply line capable of being readily decreased in length as upward progress in construction of the dam takes place.

Another important object of the present invention is to provide an air jet for sandblasting apparatus which in use will serve to deliver compressed air or other fluid under pressure at right angles to the sand feed line.

Other objects and advantages of the invention will become apparent to the reader of the following specification.

In the drawings:

30 Figure 1 represents a side elevational view of the jet incorporated in an air feed line and sand supply line.

Figure 2 is a vertical sectional view through the jet showing the same built into a T-fitting.

35 Figure 3 is a section on the line 3—3 of Figure 2.

Figure 4 is a vertical sectional view showing the jet built into an elbow.

Referring to the drawings wherein like numerals designate like parts, it can be seen in Figure 1 that numeral 5 represents the sand hopper which has the top screen 6 and which is connected by bolts and flanges 7 to the down pipe 8.

This down pipe 8 is connected by bolts and flanges 9 to the quick-acting valve unit 10, and the latter in turn is connected by bolts and flanges 11 to the pipe section 12 and the latter in turn is connected by bolts and flanges 13 to the intake side of the drum hopper 14.

50 As course upon course of concrete work is built up, as in a dam construction project, pipe sections 8 are removed. The pipe line made up of the sections 8 may be one hundred feet or more in length, and the hopper 5 which may contain as much as from ten to twelve cubic yards of sand

remains suspended from the trestle (not shown) until such time as the blasting jet 24 approaches the trestle, at which time more space is required. At this time the large hopper 5 is removed, as well as the valve 10, etc., leaving just the small 5 hopper 14, which may have a capacity of only from one to two cubic yards, to complete the remaining work and which can more readily fit into a smaller space in the trestle structure than the larger hopper 5.

10 The nipple 15 depending from the hopper 14 is connected by the reducer 16 to the pipe section 17 and the latter in turn is connected by the union 18 to the pipe section 19 and the latter in turn is connected to the quick-acting valve 20. 15 From the quick-acting valve 20 extends the pipe 21 which is threadedly disposed into the up-standing portion 22 of the inverted T-fitting 23 of the jet generally referred to by numeral 24. The externally threaded cups 25 and 26 are welded 20 together back to back as at 27. The jet tube 28 is disposed through a centrally located opening in these cups 25 and 26 and is welded to the backs as at 29 and 30. The cup 26 is threadedly disposed into the portion 31 of the T-fitting 26, 25 while the short pipe section 32 extending from the valve 33 is threadedly disposed over the cup 25. The compressed air line 34 connects to the valve unit 33.

30 The discharge end of the jet 28 terminates within the protruding portion 35 of the T-fitting 23 and has its end cut off obliquely as shown in Figure 2. The sandblasting line 36 is threadedly engaged into this portion 35, as is clearly shown in Figure 1.

35 A modification of the jet is shown in Figure 4. This fitting involves an elbow 37 the upper portion of which is internally threaded to accommodate the pipe section 21, while the lower portion is externally threaded for connection to the 40 sand blast line.

The heel portion of this elbow 37 and which is denoted by numeral 38, has an opening therein through which the jet pipe 39 extends, this jet pipe being welded as at 40 to the heel portion of 45 the elbow 37.

The inner end of the jet pipe 39 is cut off obliquely and terminates within the extending portion a of the fitting 37.

50 The outer end of the jet tube 39 extends into the socket or cup 41 which is internally threaded to receive the compressed air feed line. The jet pipe 39 is welded as at 42 to the said socket 41.

Obviously, in this construction, the air drives in a direction at right angles to the line of sand 55

feed and serves to blast the sand through the line 36 as it gravitates and is drawn into the fitting 23.

5 An air line 42 is tapped to the pipe section 12 just below the valve 10 to place the column of sand in the pipe section 12 under pressure and to act on the valve to always maintain the sand in the valve 10 mobile.

10 While the foregoing specification sets forth the invention in specific terms, it is to be understood that numerous changes in the shape, size and materials may be resorted to without departing from the spirit and scope of the invention as claimed hereinafter.

15 Having described the invention, what is claimed as new is:

In combination, a fitting having a jet therein, an air inlet to the jet, a sandblast outlet, a vertically extending feed line rising from the fitting, a substantially large hopper at the upper end of the feed line, a substantially smaller closed 5 hopper adjacent the fitting, the pipe line between the large hopper and the small closed hopper being divided into removable sections, a valve in the pipe line located below the large hopper and an air supply line connected to the feed line im- 10 mediately below the valve therein to place material in the line under the valve under pressure and to maintain material under the valve in a mobile state.

EDWARD J. FLAVIN. 15
